CARBURETOR

John H. Arff, Portland, Oreg.

Application April 23, 1935, Serial No. 17,815

3 Claims. (Cl. 261—44)

This invention relates generally to internal combustion engines, and particularly to a means for selectively using two fuels of varying degrees of specific gravity.

5 The main object of this invention is to secure the maximum amount of economy in motor operation.

The second object is to utilize the flow of air to control the fuel flow to the motor.

10 The third object is to provide a means for controlling the flow of fuel in direct relation to the air flow.

The fourth object is to provide a means for alternately handling liquids of varying degrees of specific gravity with a given vacuum pull.

The fifth object is to provide a selective means for drawing fuel from two independent sources and especially fuels of eligibly great difference in specific gravity.

20 The sixth object is to provide an improved form of valve construction.

The seventh object is the elimination of the acceleratory pump.

25 Before entering into a description of this invention, it is understood that numerous attempts have been made to satisfactorily use cheaper fuels, such as Diesel oil, in automobile engines, but the use has not become satisfactory up to the present time owing to numerous difficulties which are encountered in such attempts.

In the invention which I am about to describe a special carburetor is provided for handling the heavier fuel. This is employed in addition to the usual gasoline carburetor, and their use is selectively inter-changeable.

35 These, and other objects, will become more apparent from the specification following as illustrated in the accompanying drawings, in which:

40 Fig. 1 is a diagrammatic view showing the device installed in connection with an internal combustion engine with manifolds and the usual gasoline carburetor.

Fig. 2 is a section taken along the line 2—2 in Fig. 1.

45 Fig. 3 is a plan of the device with parts broken away to show the butterfly.

Fig. 4 is a section taken along the line 4—4 in Fig. 3.

50 Fig. 5 is a section taken along the line 5—5 in Fig. 4.

Fig. 6 is an enlarged view of the operating levers.

55 Fig. 7 is a section through a modified form of the device.

Fig. 8 is a section taken along the line 8—8 in Fig. 7.

Fig. 9 is a section taken along the line 9—9 in Fig. 7.

Fig. 10 is a section taken along the line 10—10 in Fig. 7.

Similar numbers of reference refer to similar parts throughout the several views.

Referring in detail to the drawings, there is shown an internal combustion engine 10 with the usual intake manifold 11 and exhaust manifold 12. The usual gasoline carburetor 13 is spaced from the intake manifold 11 by means of a T-fitting 14. The carburetor 13 is joined to the fuel supply tank by means of a pipe 15. The positions of the gasoline choke button 16 and butterfly 17 are also indicated.

Referring more particularly to my invention same consists of a horizontal cylindrical body 18 on whose underside is attached a fuel well 19 for Diesel fuel 20. Extending downwardly from the body 18 to the bottom of the well 19 is a central stem 21 having an opening 22 formed therein into whose lower threaded end is screwed the short screw 23, which is used to hold the well 19 up against the body 18. It is desirable to provide a packing 24 between the well 19 and the body 18.

The stem 21 is provided with holes 25 through which fuel 20 can enter the opening 22. Threaded into the body 18 is a tubular stem 26 whose upper end is provided with a valve seat 27. The portion of the cylindrical opening 28, which immediately surrounds the seat 27, is counter-sunk as shown.

Within the well 19 and surrounding the stem 21 is a float 29, the purpose of which is to maintain a fixed level of fuel 20 in the well 19. This is accomplished by providing a check valve 30 within the bushing 31 which is threaded into the body 18. The lower end 32 of the valve 30 projects below the lower end of the bushing 31 and engages a hinged arm 33 to which the float 29 is attached. The float 29 operates in a manner to close the valve 30 when the level of the fuel 20 is sufficiently high.

45 Fuel is admitted to the well 19 through the Diesel oil supply pipe 34, which extends through the exhaust manifold 12 into the vacuum tank 35 which is supplied with fuel from the Diesel oil tank, not shown, by means of the pipe 36. The usual suction line 37 from the intake manifold 11 to the vacuum tank 35 is also indicated. Projecting upwardly from the body 18 is the vertical head 38 provided with a cylindrical opening 39 which is closed by a cap 40.

Within the cylindrical opening 39 is a piston valve 41, whose lower end 42 is in the form of a hemisphere, so that when the piston 41 is down to its lowermost limit, the opening 28 is practically closed. The piston 41 is co-axial with the stem 26. Extending through the piston 41 is a needle valve 43, whose position is adjustably fixed by means of the knurled end 44 on the threaded portion 45 which is provided with a lock nut 46.

10 By this arrangement the clearance between the needle point 47 and the seat 27 may be accurately adjusted and maintained.

From opposite sides of the cap 40 extend the ears 48, which serve as guides for the vertical rods 49 whose lower ends guide in the ears 50, which project laterally from the body 18. The upper ends of the rods 49 are united by means of a yoke 51, and the position of the yoke 51 with reference to the rods 49 can be accurately adjusted by the nuts 52. Projecting downwardly from the yoke 51 are the plungers which unite the yoke 51 to the piston 41 on opposite sides of the needle valve 43. Each rod 49 is provided with a spring 54 on the underside of its respective guiding ear 48. On each rod 49, below its spring 54, is secured a pin 55. To each pin 55 is attached a lever 56, which is free to rotate on the shaft 57 of the butterfly valve 58, which is located in the opening 28.

30 The levers 56 are provided with lateral extensions 59 and elongated slots 60 which receive the pins 55. Secured near opposite ends of the shaft 57 are the levers 61, each of which is provided with a lateral extension 62 which carries an adjusting screw 63, whose end 64 can engage the extension 59. Each lever 61 is joined by a link 65 to a common pull rod 66, which is attached to one end of a spring urged lever 67, which is actuated by the Diesel foot throttle 68. The position of the gasoline foot throttle 69 is also indicated as being joined by means of the pull rod 70 to the butterfly lever 71 of the gasoline carburetor 13. The vacuum tank for the gasoline line is not illustrated, but it is joined to the pipe 72 which communicates with the intake manifold 11.

50 Turning now to the body 18, it will be noticed that there is an adjustable needle valve 73 controlling an opening 74 on the underside of the body 18. The opening 74 communicates with the horizontal opening 75 and it connects with the downwardly extending tube 76, whose lower end projects into the fuel 20. This arrangement is to provide an idling adjustment for the Diesel carburetor. In order to admit a corresponding amount of air for the idling speed, at which time the butterfly 58 is closed, there is provided an air inlet screw 77, having an inlet orifice 78 communicating by means of the lateral orifices 79 with the atmosphere. A spring 80 is provided under the head of the screw 77.

65 Unless this arrangement is provided an objectionable amount of liquid fuel will be drawn up to the opening 28 between the butterfly 58 and piston 41 at idling speeds and will naturally be drawn into the motor at the next acceleration.

70 From the foregoing it will be seen that I have provided a dual system of fueling for an internal combustion engine in which the more volatile fuel, such as gasoline, is used to warm the motor, this being done merely by depressing the gasoline foot throttle 69; the result of which is that the portion of the Diesel oil pipe 34 which passes 75 through the manifold 12 becomes heated, render-

ing same more volatile when it is delivered to the well 19. It will be noted that as the motor warms up and the Diesel oil throttle 68 is depressed, causing a pull on the rod 66, then the butterfly 58 commences to open and, depending upon the adjustment of the screw 63, the opening of the butterfly 58 is followed by an opening of the piston valve 41 and the rush of air across the counter-sunk opening surrounding the valve seat 27 produces sufficient lifting action to raise the 10 heavy Diesel oil up through the stem 26 past the needle valve point 47, where it is sprayed into the rapidly passing air and drawn into the motor. It can thus be seen that by the cooperation of the two carburetors, one designed and adjusted for 15 the handling of gasoline, and the other designed and adjusted for handling of Diesel oil and by providing suitable operating connections, it is possible for the operator to selectively use either 20 of the fuels best suited for the work at hand and condition of motor and supply available.

25 In the form of the device shown in Figs. 7 to 10 inclusive, in place of the body 18, shown in Fig. 4, there is substituted a body 81 which is secured to the T-fitting 14 by means of the bolts 82. Projecting upwardly from the body 81 and communicating thereto is a cylindrical head 83 which is closed by means of a cap 84. Within the head 83 is a piston 85, whose lower end 86 is provided with a rounded point, the curvature of which is 30 such to permit the piston 85 to form a plug or closure for the opening 87 within the body 81.

Extending across the diameter of the opening 87 and into the piston 85 is a perforated tube 88 whose lower end communicates with the helical 35 grooves 89 formed in the plug 90, the grooves 89 communicating by means of the ducts 91 with an orifice 92 which is controlled by a needle valve 93. The valve 93 is free to rotate in the threaded plug 94 which is secured within the lower end of the 40 tubular post 95, which is mounted along the axis of the piston 85, the plug 90 and the valve 93.

45 The tubular post 95 is provided with ports 96 through which fuel 97 can enter from the well 98 which is supported from the base 99 of the 45 cylindrical stove 100 through which exhaust gases pass from the engine by way of the exhaust pipe 101. The plug 90 extends through a tube 102 which draws heat from the gases passing through the stove 100 and vaporizes the fuel passing 50 spirally around the grooves disposed around the plug 90. Within the well 98 is a float 103 which actuates a needle valve 104 which controls the fuel intake pipe 34.

55 The pull rod 66 of the Diesel foot throttle (not shown) is attached to one end of a lever 105, whose opposite end is secured on a shaft 106 which extends into the body 81 and whose inner end has secured thereon a slotted lever 107, whose slot 108 engages a pin 109 which extends across 60 a slot 110 formed in the piston 85. Connected with one of the holes 111 in the lever 105 is an adjustable connecting rod 112, whose opposite end is attached to a rock lever 113 which is secured to the shaft 114 of a butterfly valve 115.

65 This form of the device is substantially the same as that described in Figs. 1 to 6 inclusive, except for the fact that a vaporizing and atomizing action within the Diesel oil carburetor is introduced, and the means for operating the piston 70 85 is much improved. It will be noted that as the piston 85 descends, the perforations in the tube 88 are successively closed thereby varying the amount of vaporized fuel which may enter 75 the body 81.

I claim:

1. An oil carburetor consisting of a tubular body having a cylindrical interior and having a hemispherical plug valve slidably mounted in the top side thereof, the upper portion of said plug being cylindrical in form and occupying a cylindrical recess formed in the upper portion of said body, said plug having a needle valve extending vertically therethrough along its major axis and having its point projecting below the bottom of said hemispherical portion, means for adjusting the position of said needle valve, a fuel well disposed on the underside of said body, a float in said well, a needle valve in said body actuated by said float, said needle valve serving to control the action of a suction line, said body having a port for venting said well to the atmosphere, a tubular connection between said well and the interior of said body the outlet end of which is controlled by said first mentioned needle valve, a butterfly valve between said plug valve and the outlet end of said body, and a valve controlled line communicating with said well and discharging a mixture of fuel and air into said body on the outlet side of said butterfly valve.

2. The device described in claim 1, together with means for actuating said plug valve in unison with said butterfly valve.

3. An oil carburetor consisting of a body having a cylindrical opening therethrough, one end of which serves as an air inlet and the other end of which communicates with the intake manifold of an internal combustion engine, said body having a cylindrical opening on its top side communicating with the main opening of said body and normal thereto, a plug valve within the vertical cylindrical opening having its lower end hemispherical in shape, a well on the underside of said body having a connection communicating between said well and the interior of said body immediately below said plug, said body having a countersunk opening around the point of connection to said well, an adjustable needle valve slidably passed through said plug for controlling the outlet of such connection, a float within said well, a suction line communicating with said well, a valve actuated by said float for controlling the action of said suction line, a butterfly valve between said plug valve and the intake manifold, and a manually operated means for simultaneously opening said butterfly and plug valves whereby the opening of said butterfly valve will cause a rush of air around the underside of said plug valve and increase the lifting action exerted against the fuel within the oil well.

JOHN H. ARFF.
